UNITED STATES PATENT OFFICE.

NATHAN BERSON, OF NEW YORK, N. Y.

VENTILATING-GRATING.

1,184,309.

Specification of Letters Patent.

Patented May 23, 1916.

Application filed May 16, 1913. Serial No. 768,128.

To all whom it may concern:

Be it known that I, NATHAN BERSON, a subject of the Czar of Russia, residing in the city of New York, county of Queens, State of New York, have invented a certain new and useful Ventilating-Grating, of which the following is a specification.

This invention is an improved grating, and the object of the invention is to simplify 10 grating construction and economize in both labor and material.

Broadly stated, the invention embodies a grating wherein the parts thereof are assembled or secured together without necessitating the employment of rivets or other independent fastening means, said means being integral with, or part of, the members which form the grating.

The invention, moreover, consists in the 20 novel method of constructing such a grating.

In the preferred embodiment of the invention herein shown, the grating embodies longitudinal members or supports, and transverse members or ties. Each of the supporting members is provided with a plurality of slots, each of which is of substantially the same dimensions as the cross section of the tie members. These tie members are passed through the said slots and are 25 provided with notches which are adapted to engage the longitudinal members adjacent to said slots. When so positioned, locking means, integral with said longitudinal members, may be manipulated, whereby each tie 30 is securely locked in position.

In the accompanying drawings, I have illustrated one practical embodiment of the invention, but the construction shown therein is to be understood as illustrative, only, 40 and not as defining the limits of the invention.

Figure 1 is a plan view illustrating a portion of a typical grating embodying the present invention. Fig. 2 is a perspective view showing a fragment of one of the longitudinal members and short lengths of two of the transverse tie members, the latter being shown in positions as they are about to enter certain slots in the former, as in the 45 process of assembling the grating. Fig. 3 is a perspective of a portion of the grating showing the parts assembled, as in the finished product. Fig. 4 is a transverse section taken on the line 4-4 of Fig. 1, illustrating the engagement between the longitudinal and tie members.

Referring to said drawings, A designates any one of a plurality of longitudinal members which are placed side by side in substantially parallel relation to one another 60 and form the principal supporting means for carrying the weight to which the grating may be subjected. These members are slotted at intervals along their length, as at B, but, in the operation of cutting out these 65 slots, a tongue is left at one end of each slot. The said tongues, owing to the fact that the grating is made from malleable material such as, e.g., wrought iron, may be bent out of the plane of the rest of their 70 respective members A, as shown, more particularly, in Fig. 2. By this bending of the tongues, the slots are opened for practically their full length so as to allow for the threading therethrough of the transverse or 75 tie members C of the grating.

The tie members are, in thickness, substantially equal to the width of the slots B, and are, in width, slightly less than the length of said slots. Each tie has a plurality of notches c, along one of its edges, said notches being of such distance apart as it is desired to space the longitudinal members A from one another, and are, in width, substantially equal to the thickness of said 85 longitudinal members. Moreover, the depth of the notches is substantially equal to the distance from the upper edges of the supporting members to the top of the slots B.

It will thus be manifest that, in assembling the parts of the grating, the tongues b are bent out and the tie members are then passed through the successive supporting members A for the entire width of the grating. When this has been accomplished, the 95 members A are arranged so that they are in juxtaposition with their respective notches c, in the tie members. The tie members are now shifted in the direction of their width, whereby the notches in said members 100 straddle that portion of the longitudinal members above the slots, by virtue of which engagement, said longitudinal members are retained against transverse movement. This having been done, the tongues are next 105 forced back into their initial position, as shown in Figs. 3 and 4, and the transverse ties thus securely locked against displacement. Furthermore, the tongues are of such length that, when forced into place, they 110 will tightly jam the bases of the notches c, in the ties C, against the upper end of the

slots B, whereby a structure of great rigidity results. Consequently, the grating will, owing to the engagement of the notches c in the ties C with the longitudinal members, have one face which is substantially flush.

When assembled, the grating is extremely neat in appearance, and greatly resembles a casting. It is adapted for many uses, but was primarily conceived to take the place of the intricate and costly constructions which are employed in covering subway vents.

By the present invention, a neat, strong, and comparatively cheap grating is provided which, aside from the simplicity of its component parts, may be assembled with ease and celerity.

Having thus fully described the invention, what I claim as new, and desire to secure by Letters Patent is:—

In a subway grating of the class described, a joint embodying, in combination, two intersecting bars each of which is substantially rectangular in cross section and one of which is wider than the other, the wider of said bars having a transverse slot, substantially equal in length to the width

of the narrower bar and equal in width to the thickness of the narrower bar, a tongue secured in one end of the slot, equal in width to the width of the slot and adapted to be positioned in alinement with the bar or out of alinement therewith, and the narrower of the two bars being provided with a notch in one of its edges only, whereby the narrower bar is adapted to be passed through the slot in the wider bar when the tongue is in a position out of alinement with said bar and shifted transversely of its length, whereupon the positioning of the tongue in alinement with the bar causes the notch in the narrower bar to engage with the larger bar adjacent the slot thereof for the purpose of locking the bars against relative movement with one of the edges of each of said bars flush.

In testimony whereof I have signed my name to this specification in the presence of two subscribing witnesses.

NATHAN BERSON.
